UNITED STATES PATENT OFFICE.

EDWIN J. WALKER, OF PHILADELPHIA, PENNSYLVANIA.

BIN.

SPECIFICATION forming part of Letters Patent No. 728,054, dated May 12, 1903.

Application filed January 29, 1902. Serial No. 91,676. (No model.)

To all whom it may concern:

Be it known that I, EDWIN J. WALKER, of Philadelphia, in the State of Pennsylvania, have invented certain new and useful Improvements in Bins, whereof the following is a specification, reference being had to the accompanying drawings.

My invention relates to pivoted or tilting bins of the class shown in my Letters Patent of the United States Nos. 550,900 and 614,279. As shown in said Letters Patent, the bearings upon which the bins tilt are part of a stationary inclosure attached to a store-wall.

It is the object of my present improvements to provide a bin of the class specified which may be lightly and durably constructed of metal, and, further, to provide a casing for such a metallic bin which is independent of the wall-fixtures aforesaid and portable, together with the bin. As hereinafter described, said portable bin-casing preferably comprises a compartment behind the bin wherein the goods may be stored, the latter feature of construction being advantageous in that only such a quantity of the goods as is desired for immediate use need be exposed in the bin.

My invention comprehends the various novel features of construction and arrangement hereinafter more definitely specified and claimed.

In the accompanying drawings, Figure I is a fragmentary front view of a cabinet conveniently embodying a plurality of my portable bins and their casings. Fig. II is a side view of said cabinet. Fig. III is a side view of the bin and casing indicated at the central portion of Fig. II. Fig. IV is a sectional view of the bin, taken on the line IV-IV in Fig. V. Fig. V is a sectional view of the bin, taken on the line V-V in Fig. IV. Fig. VI is a fragmentary plan sectional view of the rear corner of the bin indicated in Fig. IV.

In said figures, 1 is the cabinet, 2 the bin-casings, and 3 the bins. Said casings each comprise a top wall 4 and a bottom wall 5, a back wall 6, and side walls 7 and 8, respectively. The several edges of the casing-walls are bent to form narrow reinforcing-flanges 9, with the exception of the front edges of the top and bottom walls, the flanges of the

side and back walls being seated within the flanges of the top and bottom walls, as best shown in Figs. IV and V. The front edges of the top and bottom walls are bent to form wide flanges 10 and 11, respectively, and the flange 10 is turned inward to form a stop-rail 12, which engages the top of the bin when the latter is tilted forward. The reinforcing-strip 13 is transversely secured to the flange 11 and to the wall 5 of the casing to form a rigid support on which to pivot the bin. Said strip is provided with pairs of plates 14, having sockets to receive the pivot-lugs of the plates 15, fixed on the bottom of the bin 3. As shown in the drawings, the front of the bin is so constructed that a substantial portion of the contents of the bin shall be forward of said pivotal supports 14 15, such disposition of the contents serving to partially counterbalance the bin, so that when released it shall close against the front flange 10 of the top wall 4 without shock or jar.

The bin 3 comprises the back wall 16, bottom wall 17, and the upwardly-inclined front portion 18, conveniently formed in one piece. The front wall 19 and side walls 20 and 21 of said bin are conveniently formed of separate pieces and the side edges of the bottom wall 17 are turned up to form flanges 22, seated within the inwardly-turned bottom flanges 23 of said side walls. The side edges of the rear wall 16 are rigidly joined to the rear edges of the side walls 20 and 21 by the vertical reinforcing-strips 24, which are placed diagonally across the corners. The joint between said back wall 16 and the side walls 20 and 21 is further stiffened by the guard-plate 25, whose side edges are seated beneath the top edges of said side walls, which are wrapped upon the curved wire cores 26. It is to be noted that the curvature of the upper edges of the side walls 20 and 21 is such that when the bin is tilted into its forward position there is a space between said edges and the flange 10 sufficient to permit the bin to be uplifted to disengage its pivotal lugs from the reinforcing-strips 13, so that the bin may be withdrawn from its casing. Ordinarily, however, the forward movement of the bin is limited by the encounter of its top edge 27 with the stop-rail 12, said edge 27 being conveniently

reinforced by the wire core 28, around which it is wrapped. The portion of the bin immediately adjoining its pivot-lugs is stiffened by the brace-plates 29 30, which extend transversely across the bin, respectively, upon the inner and outer sides thereof, as shown in Fig. IV.

The above-described Figs. IV and V show the simple form of my invention, wherein the casing 2 is merely of such dimensions as to form a chamber for the bin 3. I find it convenient, however, to provide the bins with casings, which are extended rearwardly, as shown in Figs. II and III, so as to comprise a supplementary storage-chamber 33, separated from the bin-chamber by the vertical partition 31 and adapted to contain packages 32 of the commodity which is exposed in bulk within the bin. This form of my invention may be advantageously employed for teas, spices, and similar goods, access being had to both chambers through their common outlet at the front of the casing, which latter is manually closed by the bin-front.

As shown in the several figures, the bins 3 are provided with handles 35 to facilitate the tilting of the bin, and, as shown in Fig. IV, said handles are conveniently secured to the front wall 19 of the bin by the screw-bolts 36, engaged with the nuts 37.

It is to be understood that the various sheet-metal portions of the bin which are permanently united may be joined by soldering their engaged flanges or by rivets or by any suitable means.

I do not desire to limit myself to the precise details of construction and arrangement which I have shown and described, as it is obvious that various modifications may be made therein without departing from the essential features of my invention.

I claim—

1. The combination with a metallic bin-casing comprising a portable bin-chamber, provided with pivotal members at the front edge of its bottom wall; of a metallic bin tiltably mounted in said casing and provided with pivotal members secured to the front edge of its bottom wall, adapted to removably engage the pivotal members in said casing; and brace-plates respectively within and without said bin, adjoining said pivotal members, substantially as set forth.

2. The combination with a metallic bin-casing comprising a portable bin-chamber provided with pivotal members at the front edge of its bottom wall; of a metallic bin tiltably mounted in said casing and provided with pivotal members secured to the front edge of its bottom wall adapted to removably engage the pivotal members of said casing; and a brace-plate within said bin adjoining said pivotal members, substantially as set forth.

3. The combination with a metallic bin-casing comprising a portable bin-chamber;

of a reinforcing-strip 13 secured at the front edge of the bottom wall of said casing, enclosing a recess; pivotal plates fixed upon the top of said reinforcing-strip, comprising 70 sockets opening through said strip into said recess; a metallic bin provided with pivotal members secured to the front edge of its bottom wall and tiltably mounted in said casing in engagement with said sockets, substantially as set forth.

4. The combination with a metallic bin-casing comprising a portable bin-chamber; of a reinforcing-strip 13 secured at the front edge of the bottom wall of said casing, enclosing a recess; pivotal plates mounted upon said reinforcing-strip and connected through the latter, comprising sockets opening through said strip into said recess; a metallic bin provided with pivotal members secured to 85 the front edge of its bottom wall and tiltably mounted in said casing in engagement with said sockets, substantially as set forth.

5. The combination with a metallic bin-casing comprising a portable bin-chamber; 90 of a reinforcing-strip secured at the front edge of the bottom wall of said casing enclosing a recess; pivotal plates mounted respectively within and without said reinforcing-strip and connected through the latter, 95 comprising sockets opening through said strip into said recess; and, a metallic bin, provided at the front edge of its bottom wall with pivotal plates within and without said wall, and connected through the latter, tiltably mounted in said casing in engagement with said sockets, substantially as set forth.

6. The combination with a casing comprising a bin-chamber and a supplementary storage-chamber having a common outlet; of a 105 reinforcing-strip at the bottom of said outlet; pivotal socket members mounted on said reinforcing-strip; and, a removable bin normally closing said common outlet, provided with pivotal members fitted to said sockets 110 and tiltably mounted in said casing, substantially as set forth.

7. The combination with a casing; of a partition 31 extending vertically from the bottom of said casing and terminating intermediate of the height of said casing, dividing said casing into a bin-chamber and a storage-chamber having a common outlet; a reinforcing-strip at the bottom of said outlet; pivotal socket members mounted on said reinforcing-strip; and, a removable bin normally closing said common outlet, provided with pivotal members fitted to said sockets 115 and tiltably mounted in said casing, substantially as set forth.

8. The combination with a casing comprising a bin-chamber and a supplementary storage-chamber having a common outlet; of a reinforcing-strip 13 at the bottom of said outlet; pivotal socket members 14 mounted 120 on said reinforcing-strip; and, a removable bin normally closing said common outlet,

provided with pivotal members fitted to said sockets and tiltably mounted in said casing, said bin having a counterbalance front projecting forward from said casing above said 5 reinforcing-strip, substantially as set forth.

9. The combination with a metallic bin-casing, comprising walls having flanged edges by which said walls are connected together and form a bin-chamber; of a stop-rail 12 fixed 10 to the top wall of said chamber at the front thereof; an angular reinforcing-strip 13 secured at the front edge of the bottom wall of said casing; pivotal socket-plates 14 mounted upon the top of said reinforcing-strip; a

removable metallic bin pivotally connected to 15 said reinforcing-strip, and comprising a back wall whose upper edge 27 is wrapped upon a wire core 28 and arranged to encounter said stop-rail 12 and limit the forward movement of the bin, substantially as set forth. 20

In testimony whereof I have hereunto signed my name, at Philadelphia, Pennsylvania, this 28th day of January, 1902.

EDWIN J. WALKER.
